THREAD PRINTING APPARATUS SELECTOR
MECHANISM

Daniel Butler Bonner, Philadelphia, Pa.

Application November 7, 1935, Serial No. 48,650

18 Claims. (Cl. 91—12.01)

This invention relates to improvements in selector mechanisms for thread printing apparatus of the type disclosed in my Patents Nos. 1,852,641, 1,854,366 and 1,905,138.

One of the primary objects of my invention resides in the provision of improved selector mechanism for controlling the rotation of the thread carrying drum of apparatus of the above character to prescribed different printing positions in which the selectors are automatically brought into selective position in a simple and effective manner.

Another object of my invention resides in the provision of ribbon controlled selector mechanism for apparatus of the class described.

A more specific object of my invention resides in the provision of a selector wheel having yieldable selectors adapted to be automatically pre-selected through the medium of ribbon control.

A further object of my invention resides in the provision of automatic selector mechanism for apparatus of the class described employing a ribbon which is adapted to automatically effect pre-selection of selector devices in the order desired as rotation of the thread carrying drum of the apparatus progresses.

Still another object of my invention is the provision of ribbon controlled selector mechanism which is adapted to effect pre-selection of the selectors for a plurality of colors to be printed on the thread without the necessity of changing ribbons for each color.

How the foregoing, together with such other objects and advantages as may hereinafter appear, or are incident to my invention, are realized is illustrated in preferred form in the accompanying drawings, wherein—

Figure 1 is a fragmentary elevational view of my improved selector mechanism illustrated as applied to thread printing apparatus such as disclosed in my above-mentioned patents;

Figure 2 is an end elevational view of Figure 1 looking toward the left;

Figure 3 is an enlarged fragmentary cross-sectional view through the selector wheel, taken on the line 3—3 of Figure 1;

Figure 4 is a sectional view taken on the line 4—4 of Figure 3;

Figure 5 is a fragmentary view illustrating a modification of my invention; and

Figures 6 to 10 inclusive are fragmentary views illustrating an arrangement of apertures in the ribbon of the selector mechanism.

The thread printing apparatus disclosed comprises in general a drum A on which the thread

is wound in a single layer composed of a number of threads extending for the width of the drum; a printing carriage B adapted to travel back and forth in the axial direction of the drum and having a printing roll C contacting with the layer of thread on the drum to print transverse stripes of color thereon; driving mechanism D for rotating the drum when the printing mechanism is out of operation; and driving mechanism E for rotating the drum in steps when printing is being effected, all in the manner disclosed in my above previous patents.

The driving mechanism D may be referred to as a skipping mechanism or a mechanism for imparting rotative movement to the drum of greater amplitude than the step movement imparted to the drum by the driving mechanism E. The drum A is rigidly secured to a shaft 6 which carries a gear 7.

Referring first to the driving mechanism E for rotating the drum in uniform steps, i. e., in a plurality of intermittent rotative movements, it will be seen that such movement is imparted through the medium of a pawl and ratchet device F. The device F comprises a ratchet wheel 8 rigidly secured to a shaft 9 on which a pinion 10 meshing with the gear 7 is splined. The ratchet wheel 8 is provided with evenly spaced ratchet teeth, in this particular instance one hundred and eight teeth being provided. A pawl 11 is adapted to engage the teeth of the ratchet wheel and is operated to engage a tooth of the wheel, rotate it with the drum through the medium of the pinion 10 meshing with the gear 7 a distance equal to the spacing of the teeth, then ratchet back to engage the next tooth, then advance the wheel and drum another notch, and so on. The pawl 11 is operated from a cam 12 which actuates the pawl through suitable lever mechanism comprising a lever 13 pivoted at 14 to the framework of the machine and having a cam roller 15 at one end contacting with the cam and connected adjacent its other end to an arm 16 by means of a link 17. The arm 16 is secured to a rock shaft 18 which carries a second upwardly extending arm 19 so that, in effect, the arms 16 and 19 and rock shaft 18 constitute a bell crank lever. The pawl 11 is pivotally mounted on an arm 20 mounted on the ratchet wheel shaft 9 for oscillation and is connected to the arm 19 by means of a link 21. The cam lever 13 is maintained in engagement with the cam by means of a spring 22 secured at one end to the lever and at the other end to the frame of the machine. Two oppositely disposed depre-

sions 23 are provided in the cam surface so that the pawl is operated twice for each revolution of the cam.

The cam 12 is driven from a drive shaft 24 having a pinion 25 idly mounted thereon and meshing with a gear 26 secured on the cam shaft 27. A clutch G controls the pinion 25 for a purpose hereinafter appearing. The drive shaft 24 may be driven in any suitable manner as by means of a drive belt 28 and drive pulley 29. A clutch device H is provided for connecting and disconnecting the pulley 29 with the drive shaft 24.

The printing carriage B is operated in back and forth movement by means of a crank 30 and connecting rod 31, the crank being carried by the cam shaft 27 and the operation being after the manner disclosed in my above-mentioned patents, from which it will be seen that when the cam shaft rotates, the printing carriage with its printing roll traverses the face of the large drum A so that stripes of color are deposited by the printing roll which is in contact with the thread. It is pointed out that the cam 12, the crank 30, and the length of travel of the carriage 20 relative to the width of the drum A are so calculated that the rotation of the drum by the mechanism E does not start until the printing roll C is out of contact with the thread and is completed before the roll again contacts with the thread.

30 The apparatus as thus far described would only take care of printing a multiplicity of transverse stripes across the layer of threads, the spacing of which would correspond to the spacing of the teeth of the ratchet wheel 8, and with close spacing of the teeth would result in substantially solid coloring of the layer of thread. However, since I propose to print stripes of different colors on the layer of thread in various arrangements according to the requirements for producing a desired 35 design in the material into which the thread is ultimately to be fabricated, I have provided mechanisms cooperating with the above to make this possible. For example, it may be desired to employ four different colors—brown, green, old 40 rose, and black—and the ultimate design to be produced may require that the layer of thread be printed with three stripes of brown, followed by three stripes of green, two stripes of old rose, three stripes of brown, two stripes of black, three 45 stripes of green, two stripes of black, three stripes of brown, two stripes of old rose, three stripes of green, three stripes of brown, and so on.

In order to accomplish this I print all of the stripes of one color in their proper spacing for 55 the entire circumference of the drum. This, of course, means that spaces must be left between the stripes of the particular color being printed to accommodate the remaining colors. The means for selecting the points where stripes are 60 to be printed and for causing skipping where spaces are to be left, will be described presently. After having printed one color I lift out the removable well 32 and its printing roll, and insert a roll and well containing the coloring liquid of 65 the next color to be printed, and then resume printing stripes of this color in proper spacing relative to the first stripes which were printed, and so on until all of the colors have been printed.

70 The selector or control mechanism just above referred to comprises a selector wheel 33 which may be integral with the ratchet wheel 8, a plurality of selector pins 34 carried by the selector wheel, and ribbon means indicated as a whole by the reference letter K. The selector pins 34 75 are mounted in radially disposed holes 35 in the

rim portion of the selector wheel, the holes being located from the teeth of the ratchet wheel 8 and there being one hole for each tooth. The pins 34 are spring-projected from the face of the wheel by means of springs 36 engaging shoulder portions 37 provided on the pins. The other ends of the springs engage a ring 38 which may be secured in place as by means of screws 39. The pins 34 are limited in their outward movement by means of the shoulder portions 37 engaging 10 the reduced portions of the holes 35.

The selector pins 34 are set into selective position by means of the ribbon device K which comprises a ribbon 40, preferably made of metal, which is unwound from a reel or magazine 41 15 and passed over the selector wheel 33 and then led to the winding-up reel 42. A guide roller 43 is provided between the reel 41 and the selector wheel, and the selector wheel is provided with a peripheral groove 44 to laterally position the ribbon on the wheel. A plurality of evenly spaced holes 45 are provided adjacent one edge of the ribbon for engagement with dowel pins 46 carried by the wheel and equally spaced circumferentially thereof. In this instance, I have illustrated four such dowels in the selector wheel and the dowel holes 45 in the ribbon are correspondingly spaced. These dowels serve to pull the ribbon over the selector wheel as it rotates.

The reel 42 is provided for winding up the ribbon after it passes over the selector wheel, and is driven as by means of a belt drive comprising a belt 47, a pulley 48 secured to the shaft 49 on which the reel 42 is mounted, a belt tightening pulley 50 rotatively mounted adjacent one end 30 of an arm 51 which is pivoted at 52, a lower idler pulley 53, and a pulley 54 secured on the shaft 9 and of substantially the same diameter as the selector wheel 33. It will thus be seen that drive is imparted to the reel 42 from the selector wheel 40 shaft 9 in a direction to wind up the ribbon. In order to compensate for the increase in diameter of the ribbon as it is wound onto the reel 42, I have provided means for slipping the belt which comprises the arm 51 and pulley 50 just mentioned and a pulley 55 rotatively mounted adjacent the end of the lever 51 opposite the end at which the pulley 50 is mounted. This pulley 55 rides on the ribbon 40 and is spring-pressed thereagainst by means of a spring 56 which is 50 secured at one end to a fixed part of the machine and at the other end to the lever 51. It will thus be seen that as the reel 42 tends to wind up the ribbon faster than the rate at which it leaves the selector wheel, the run of ribbon between the 55 selector wheel and the reel will become tensioned, thus causing the upper end of the lever 51 to move to the right and the lower end to the left, which loosens the belt accordingly and allows slippage to take place and thus prevents breaking 60 of the ribbon. In order to prevent the ribbon from unwinding off the reel 41 too fast, I employ a friction brake 57 adapted to be adjusted as by means of a bolt 58. The reels 41 and 42 are provided with square holes adapted to fit the 65 squared portions of their shafts 59 and 49, respectively.

The ribbon 40 is provided with a plurality of holes 60 which are spaced therealong to correspond to the spacing of the stripes of color to be 70 printed on the drum. As the ribbon is passed over the selector wheel, these holes register with corresponding pins and allow them to project through the ribbon, as indicated in Figures 1, 3 75 and 4, while the remaining pins which do not

register with holes are held in retracted or depressed position by the blank or imperforate portions of the ribbon.

Assuming now that it is desired to print the thread in four colors in accordance with the example given above, then the first portion of the ribbon is provided with holes corresponding to the brown stripes to be printed as illustrated in Figure 6, in which, starting from the bottom, there are three holes spaced to correspond to the spacing of the pins on the selector wheel so that three pins will be spring pressed or projected therethrough, then a blank section for depressing the next five pins, then three holes from which the next three pins project, then a blank section for depressing the next seven pins, then three holes through which the next three pins project, then a blank section for depressing the next five pins, and then three holes through which the next three pins project and so on as illustrated. In order to readily see from inspection of Figures 6 to 10, inclusive, how many pins are depressed by the blank sections of the ribbon between apertures, I have indicated the depressed pins by dots. In Figure 6, the portion of the ribbon which extends between the lines X and Y is equal to the circumference of the selector wheel 33 and by the time this portion of the ribbon has traversed the selector wheel the particular arrangements of stripes exemplified has been repeated twice on the thread carried by the drum. The selector wheel makes six revolutions to one revolution of the drum and, therefore, an amount of tape equal to six times the circumference of the selector wheel will traverse the wheel and the particular arrangement of stripes just referred to will be repeated twelve times for the circumference of the drum. Following this portion of the ribbon there is another section or portion which is equal to six times the circumference of the selector wheel in which the holes are arranged to correspond to the arrangement of the stripes of green which are to be printed on the threads. The next section of ribbon equal to six times the circumference of the selector wheel has the holes arranged to correspond to the arrangement of the stripes of old rose which are to be printed on the threads and the final section or portion of the ribbon equal to six times the circumference of the selector wheel has the holes arranged to correspond to the arrangement of the stripes of black which are to be printed on the threads. In Figures 7, 8, 9 and 10, short sections of each of these four portions of the ribbon are illustrated with the holes shown in their relative positions, although it is to be understood that the particular ribbon illustrated in Figure 1 is of one continuous piece and includes holes properly arranged to effect printing of all four colors. When setting the machine for operation, the ribbon is unrolled from the reel 41 until the first hole therein registers with the pin 34a which is adjacent the roller 61 of a trip arm 61a and a brown ink-well and roller are placed in the printing carriage. The operator then moves the operating bar 62 to cause engagement of the clutch H which effects drive from the pulley 29 to the shaft 24. As has been pointed out above, the shaft 24 carries the loose pinion 25 adapted to be drivably connected to the shaft by means of the clutch device G and this pinion meshes with the gear 26 secured to the cam shaft 27. The drive shaft 24 carries a second loose pinion 63 meshing with a gear 64 mounted to freely rotate on the cam shaft 27. A sprocket wheel 65

is secured to the gear 64 and drive is transmitted from this gear to a shaft 66 located therebelow by means of the sprocket wheel 65, chain 67 and sprocket wheel 68. The shaft 66 has a bevel gear 69 rigidly secured thereon which meshes with a beveled gear 70 rigidly secured to the ratchet wheel shaft 9. A clutch device J is provided for the purpose of drivably connecting the pinion 63 to the shaft 24.

It will thus be seen that when the clutches H and J are engaged drive is transmitted from the shaft 24 to the drum A through the medium of the pinion 63, gear 64, sprocket 65, chain 67, sprocket wheel 68, bevel gears 69 and 70, pinion 10 and drum gear 7, it being pointed out that the pinion 10 is moved into mesh with the gear 7 when printing operations are to take place as by means of a shaft arm 71. The clutches G and J above mentioned are controlled by the selector mechanism as will now appear.

Referring, now, more particularly to Figures 1 and 2, the selector wheel 33 is shown in a position so that a space of the wheel where no pins project is presented to the roller of the trip arm 61a. With the trip arm 61a in the position illustrated the clutch J will be engaged and the clutch G disengaged because of the following provisions. The trip arm 61a is pivoted at 72 and the end portion thereof which is opposite the roller 61 engages a roller 73 carried by the lever 74 which is pivoted at 75. At the other end this lever is connected to a pivoted arm 76 by means of a link 77. The arm 76 is pivoted at 78 and has its free end forked to straddle a pin 79 carried by the lever 80 mounted to pivot on a rock shaft 81 carried by a bracket 82. The rock shaft 81 also has a clutch operating yoke 83 secured thereon for operating the movable member of the clutch G.

The lever 80 is provided with an inclined slot 84 at its upper end adapted to receive a roller 85 mounted on a movable bar 86. The bar 86 is mounted to reciprocate in a lever arm 87 which is secured to the rock shaft 81 to rock therewith. The movable member of the clutch G is connected to the movable member of the clutch J by means of a strap-like member 88.

Following through the mechanism just described and assuming that the selector wheel 33 is rotating in the direction of the arrow of Figure 1, it will be seen that when the projecting pin 34a engages the roller 61 of the trip arm 61a the trip arm is rocked in a direction to cause the upper portion of the lever 80 to move to the right so that the roller 85 and bar 86 are moved downwardly. When this bar moves downwardly it clears a pair of cams 89 carried by the cam shaft gear 26 and as soon as the clearance afforded by the slot 90 in the arm 87 is taken up by the downward movement of the bar 86, the arm 87 is rotated to the right, thus causing the rock shaft 81 and clutch yoke 83 to move in the same direction and thereby cause the clutch G to become engaged. Upon engagement of the clutch G the pinion 25 is clutched to the shaft 24 to receive drive therefrom, so that the pinion will rotate the gear 26 and the pawl and ratchet device F is operated in the manner hereinbefore described. At the same time that the clutch G is thus engaged the clutch J is disengaged because of the connecting member 88 and the above ratchet operation of the drum continues as long as projecting selector pins are presented to the trip arm 61a and in the case of only one pin being presented at a time only one ratchet movement 75

would take place at a time. On the other hand, if pins are located in successive holes, as the first three pins are in this instance, three successive ratchet movements take place so that the drum is rotated step by step for three steps with the clutch J disengaged and the clutch G engaged, and the printing carriage B is operated to travel back and forth and the drum is rotated by ratchet or step-by-step movement, all as above described, it being noted that the drive shaft 24 is common to both devices B and E.

As soon as the third of these first three pins passes the roller of the trip arm 61a the trip arm is returned to the position illustrated in Figures 1 and 2, which causes the bar 86 to move upwardly under influence of a spring 91 and in which position the bar will be in the path of the cams 89. As soon as the cam surface of the nearest cam comes around it engages the bar 86 and positively rocks the lever arm 87, lever 80 and clutch yoke 83 and their associated parts in a direction to disengage the clutch G and engage the clutch J. The cams 89 are also provided with stop shoulders adapted to engage the block to stop the wheel 26 and then rotation of the drum is caused by the pinion 10 and drum gear 7, the pinion 10 receiving its drive from the shaft 24 through the medium of the transmission above described.

With the stopping of the wheel 26 the back and forth motion of the printing carriage is stopped as is also the intermittent or step-by-step movement of the drum 8, and the drum rotates in continuous movement until another selector pin is presented to the roller 61 and the lever 61a. Thus it will be seen that the drum is rotated relatively fast from one position of print to the next by means of the skipping mechanism just described. By referring to Figure 6 it will be seen that there are considerable blank spaces where no prints are to take place and, therefore, the time required to apply all the prints to the drum is materially shortened over the time it would take if ratchet movement were employed throughout the operation. After one color has been printed for a complete revolution of the drum the machine is automatically stopped as by means of an electro-magnetically operated latch device 92 which controls the clutch H as illustrated in Figure 1. When the drum has made a complete revolution the contact 93 carried by the drum engages the fixed contact 94 to energize the electromagnet 95, thus causing the latch 92 to be retracted. The bar 62 is then spring pulled to the left to release the clutch H and stop the machine. The wheel and ink roll are then replaced by a well and roll for the next color and the machine is again started by pulling the clutch bar 62 to the right which sets the latch device 92 to the position shown in Figure 1. Since the ribbon 40 is of a length to accommodate holes for all of the colors to be printed the portion thereof which has been perforated for the next color now operates on the selector wheel and the stripes for this color are selected and printed in the same manner as above described.

Although I have given an example in which four colors are employed and printed in a certain order it is to be understood that a greater or less number of colors may be employed and printed in any order desired to produce any particular arrangement of color stripes on the thread, it being pointed out that for each color added the ribbon 40 is correspondingly lengthened.

It will be seen from the foregoing that the ratio

of the gearing for the selector wheel is such that the ratchet wheel 8 makes six revolutions to one revolution of the drum and, therefore, if the ratchet wheel is provided with one hundred and eight teeth as above mentioned, the drum A will be moved to six hundred and forty-eight different printing positions in one of its revolutions.

Referring to the modification illustrated in Figure 5, I have therein illustrated an arrangement in which an endless selector ribbon 96 is employed of such length as to effect pre-selection of printing positions for stripes of only one color. This ribbon is held in proper tension by means of a spring pressed idler pulley 97 and receives its drive from the selector wheel which is provided with dowels engaging registering holes in the ribbon in a manner similar to that described in connection with the preferred form of my invention. When this type of ribbon is employed after stripes of one color have been printed on the drum 20 the ribbon is removed and a similar ribbon having perforations corresponding to the stripes of the next color to be printed is inserted in place thereof. The operation of the machine with this ribbon is the same as with the ribbon 40 above 25 described.

I claim:

1. In selector mechanism for thread printing apparatus having a rotatable thread carrying drum, drive means for imparting step-by-step rotation to the drum in steps of predetermined amplitude, drive means for imparting continuous rotation to the drum through distances of greater amplitude than such step movement, and control means for said drive means; the combination of 35 a selector wheel, selector devices carried by said wheel, and means for automatically pre-selecting selector devices to operate said control means to effect rotation of the drum through the medium of either of said drive means.

2. In selector mechanism for thread printing apparatus having a rotatable thread carrying drum, drive means for imparting step-by-step rotation to the drum in steps of predetermined amplitude, drive means for imparting continuous rotation to the drum through distances of greater amplitude than such step movement, and control means for said drive means; the combination of 45 automatic selective means for determining which movement is to be imparted to the drum comprising a selector wheel, selector devices carried by said wheel for operating said control means, and means for setting the selector devices in predetermined setting.

3. In selector mechanism for thread printing apparatus having a rotatable thread carrying drum, drive means for imparting step-by-step rotation to the drum in steps of predetermined amplitude, drive means for imparting continuous rotation to the drum through distances of greater 60 amplitude than such step movement, and control means for said drive means; the combination of automatic selective means for determining which movement is to be imparted to the drum comprising a selector wheel, selector devices carried 65 by said wheel for operating said control means, and ribbon means for setting the selector devices in predetermined setting.

4. In selector mechanism for thread printing apparatus having a rotatable thread carrying 70 drum, drive means for imparting step-by-step rotation to the drum in steps of predetermined amplitude, drive means for imparting continuous rotation to the drum through distances of greater amplitude than such step movement, and 75

control means for said drive means; the combination of automatic selective means for determining which movement is to be imparted to the drum comprising a selector wheel, yieldable selector pins carried by said wheel for operating said control means, and a movable ribbon having holes therein of predetermined spacing registering with pins to be set in selective position.

5. In selector mechanism for thread printing apparatus having a rotatable thread carrying drum, drive means for imparting step-by-step rotation to the drum in steps of predetermined amplitude, drive means for imparting continuous rotation to the drum through distances of greater 10 amplitude than such step movement, and control means for said drive means; the combination of automatic selective means for determining which movement is to be imparted to the drum comprising a selector wheel, spring pressed selector pins 15 circularly arranged on said wheel to normally project therefrom and effect operation of said control means, and a movable perforated ribbon associated with said wheel and pins and adapted to hold the pins located between perforations in 20 retracted position and to permit pins registering with the perforations to move into projected position.

6. In selector mechanism for thread printing apparatus having a rotatable thread carrying drum, drive means for imparting step-by-step rotation to the drum in steps of predetermined amplitude, drive means for imparting continuous rotation to the drum through distances of greater 25 amplitude than such step movement, and control means for said drive means; the combination of automatic selective means for determining which movement is to be imparted to the drum comprising a selector wheel, spring pressed selector pins 30 circularly arranged on said wheel to normally project therefrom and effect operation of said control means, a movable ribbon associated with said wheel and pins, and holes in said ribbon registering with corresponding pins, said ribbon being adapted to permit said registering pins to 35 project and to hold non-registering pins in retracted position.

7. In selector mechanism for thread printing apparatus having a thread carrying drum, and means for rotating said drum; the combination of 40 a rotatable selector wheel, a plurality of spring projected selector pins mounted circumferentially of said wheel in equal spacing, and an apertured ribbon passing over said wheel, the number of apertures and the relative location thereof being 45 predetermined, said ribbon in passing over said wheel permitting pins which register with the apertures to be spring projected and holding the non-registering pins in retracted position, and means controlling the rotation of said drum 50 rotating means through the medium of said selector pins.

8. In selector mechanism for thread printing apparatus having a thread carrying drum, and means for rotating said drum; the combination of 55 a selector wheel, spring projected selector pins carried by said wheel, an apertured ribbon passing over said wheel for holding certain of said pins in retracted position and enabling other pins to be 60 spring pressed into selective position, means controlling the rotation of said drum rotating means through the medium of said selector pins, a reel onto which said ribbon is wound after passing over said wheel, driving means for rotating said 65 reel to wind up the ribbon, and means for effect-

ing slippage between said driving means and said reel.

9. In selector mechanism for thread printing apparatus having a thread carrying drum, and means for rotating said drum; the combination of 10 a selector wheel, spring projected selector pins carried by said wheel, an apertured ribbon passing over said wheel for holding certain of said pins in retracted position and enabling other pins to be spring pressed into selective position, means 15 controlling the rotation of said drum rotating means through the medium of said selector pins, a reel onto which said ribbon is wound after passing over said wheel, driving means for rotating said reel to wind up the ribbon, and means operable by said ribbon for effecting slippage of said driving means.

10. In selector mechanism for thread printing apparatus having a thread carrying drum, and means for rotating said drum; the combination of 20 a selector wheel, spring projected selector pins carried by said wheel, an apertured ribbon passing over said wheel for holding certain of said pins in retracted position and enabling other pins to be spring pressed into selective position, means 25 controlling the rotation of said drum rotating means through the medium of said selector pins, a reel onto which said ribbon is wound after passing over said wheel, driving means for rotating said reel to wind up the ribbon, and means 30 operable by said ribbon for effecting slippage of said driving means proportional to the tension on the ribbon.

11. In selector mechanism for thread printing 35 apparatus having a rotatable thread carrying drum, drive means for imparting step-by-step rotation to the drum in steps of predetermined amplitude, drive means for imparting continuous rotation to the drum through distances of 40 greater amplitude than such step movement, and control means for said drive means; the combination of automatic selective means for determining which movement is to be imparted to the drum comprising a selector wheel, selector devices 45 carried by said wheel for operating said control means, and endless ribbon means for setting the selector devices in predetermined setting.

12. Selector mechanism for thread printing apparatus comprising a selector wheel, a plurality 50 of selector pins mounted circumferentially of said wheel in equal spacing, springs associated with said pins normally urging them into projected position, a ribbon passing over said wheel having apertures registering with certain pins to permit 55 them to be spring projected and having blank portions between the apertures to hold non-registering pins in retracted position, and clutch means actuated by said projecting selector pins.

13. Selector mechanism for thread printing 60 apparatus comprising a selector wheel, a plurality of selector pins mounted circumferentially of said wheel in equal spacing, springs associated with said pins normally urging them into projected position, a ribbon passing over said wheel 65 having apertures registering with certain pins to permit them to be spring projected and having blank portions between the apertures to hold non-registering pins in retracted position, clutch means actuated by said projecting selector pins, means on said selector wheel engaging the ribbon for moving the ribbon over said wheel, and take up reel means for winding up the ribbon after it passes over the wheel.

14. Selector mechanism for thread printing 75

apparatus comprising a selector wheel, a plurality of selector pins mounted circumferentially of said wheel in equal spacing, springs associated with said pins normally urging them into projected position, a ribbon passing over said wheel having apertures registering with certain pins to permit them to be spring projected and having blank portions between the apertures to hold non-registering pins in retracted position, clutch means actuated by said projecting selector pins, means on said selector wheel engaging the ribbon for moving the ribbon over said wheel, and take up reel means for winding up the ribbon after it passes over the wheel, said reel means including slippage means compensating for the increase in diameter of the ribbon wound on the reel.

15. In selector mechanism for thread printing apparatus having a rotatable thread carrying drum, drive means for imparting step-by-step rotation to the drum in steps of predetermined amplitude, drive means for imparting continuous rotation to the drum through distances of greater amplitude than such step movement, and control means for said drive means; the combination of automatic selective means for determining which movement is to be imparted to the drum comprising a selector wheel, selector devices carried by said wheel for operating said control means, endless ribbon means for setting the selector devices in predetermined setting, and means on said selector wheel engaging the ribbon for moving the ribbon over said wheel.

20. In selector mechanism for thread printing apparatus having a rotatable thread carrying drum, drive means for imparting step-by-step rotation to the drum in steps of predetermined amplitude, drive means for imparting continuous rotation to the drum through distances of greater amplitude than such step movement, and control means for said drive means; the combination of automatic selective means for determining which movement is to be imparted to the drum comprising a selector wheel, selector devices carried by said wheel for operating said control means, endless ribbon means for setting the selector devices in predetermined setting, and means on said selector wheel engaging the ribbon for moving the ribbon over said wheel.

25. In selector mechanism for thread printing apparatus having a rotatable thread carrying drum, drive means for imparting step-by-step rotation to the drum in steps of predetermined amplitude, drive means for imparting continuous rotation to the drum through distances of greater amplitude than such step movement, and control means for said drive means; the combination of automatic selective means for determining which movement is to be imparted to the drum comprising a selector wheel, selector devices carried by said wheel for operating said control means, endless ribbon means for setting the selector devices in predetermined setting, and means on said selector wheel engaging the ribbon for moving the ribbon over said wheel.

30. In selector mechanism for thread printing apparatus having a rotatable thread carrying drum, drive means for imparting step-by-step rotation to the drum in steps of predetermined amplitude, drive means for imparting continuous rotation to the drum through distances of greater amplitude than such step movement, and control means for said drive means; the combination of automatic selective means for determining which movement is to be imparted to the drum comprising a selector wheel, selector devices carried by said wheel for operating said control means, endless ribbon means for setting the selector devices in predetermined setting, and means on said selector wheel engaging the ribbon for moving the ribbon over said wheel.

35. In selector mechanism for thread printing apparatus having a rotatable thread carrying drum, drive means for imparting step-by-step rotation to the drum in steps of predetermined amplitude, drive means for imparting continuous rotation to the drum through distances of greater amplitude than such step movement, and control means for said drive means; the combination of automatic selective means for determining which movement is to be imparted to the drum comprising a selector wheel, selector devices carried by said wheel for operating said control means, endless ribbon means for setting the selector devices in predetermined setting, and means on said selector wheel engaging the ribbon for moving the ribbon over said wheel.

40. In selector mechanism for thread printing apparatus having a rotatable thread carrying drum, drive means for imparting step-by-step rotation to the drum in steps of predetermined amplitude, drive means for imparting continuous rotation to the drum through distances of greater amplitude than such step movement, and control means for said drive means; the combination of automatic selective means for determining which movement is to be imparted to the drum comprising a selector wheel, selector devices carried by said wheel for operating said control means, endless ribbon means for setting the selector devices in predetermined setting, and means on said selector wheel engaging the ribbon for moving the ribbon over said wheel.

45. In selector mechanism for thread printing apparatus having a rotatable thread carrying drum, drive means for imparting step-by-step rotation to the drum in steps of predetermined amplitude, drive means for imparting continuous rotation to the drum through distances of greater amplitude than such step movement, and control means for said drive means; the combination of automatic selective means for determining which movement is to be imparted to the drum comprising a selector wheel, selector devices carried by said wheel for operating said control means, endless ribbon means for setting the selector devices in predetermined setting, and means on said selector wheel engaging the ribbon for moving the ribbon over said wheel.

means for setting the selector devices in predetermined setting, means on said selector wheel engaging the ribbon for moving the ribbon over said wheel, and tension means for holding the ribbon in driving engagement with the selector wheel.

17. In selector mechanism for thread printing apparatus having a rotatable thread carrying drum, drive means for imparting step-by-step rotation to the drum in steps of predetermined amplitude, drive means for imparting continuous rotation to the drum through distances of greater amplitude than such step movement, and control means for said drive means; the combination of automatic selective means for determining which movement is to be imparted to the drum comprising a selector wheel, yieldable selector pins carried by said wheel for operating said control means, and a movable ribbon having holes therein of predetermined spacing registering with pins to be set in selective position, said ribbon being of a length to accommodate holes for the setting of selector pins to effect the printing of stripes for a plurality of colors.

18. In selector mechanism for thread printing apparatus having a rotatable thread carrying drum, drive means for imparting step-by-step rotation to the drum in steps of predetermined amplitude, drive means for imparting continuous rotation to the drum through distances of greater amplitude than such step movement, and control means for said drive means; the combination of automatic selective means for determining which movement is to be imparted to the drum comprising a selector wheel, yieldable selector pins carried by said wheel for operating said control means, and a movable ribbon having holes therein of predetermined spacing registering with pins to be set in selective position, said ribbon being of a length to accommodate holes for the setting of selector pins to effect the printing of stripes for a plurality of colors, together with means for automatically stopping the apparatus after all of the stripes of a color have been printed on the thread.

DANIEL BUTLER BONNER.
